ATTORNEY.

UNITED STATES PATENT OFFICE.

JAMES WARD PACKARD, OF NEW YORK, N. Y.

REVOLVING PHOTOMETER-STAND.

SPECIFICATION forming part of Letters Patent No. 396,951, dated January 29, 1889.

Application filed May 19, 1888. Serial No. 274,435. (No model.)

To all whom it may concern:

Be it known that I, JAMES WARD PACKARD, a citizen of the United States, residing at New York, in the county of New York and State of New York, have invented certain new and useful Improvements in Revolving Photometer-Stands; and I do hereby declare the following to be a full, clear, and exact description of the invention, such as will enable others skilled in the art to which it appertains to make and use the same.

My invention consists in a revolving photometer-stand for incandescent lamps and the combination of the same with the other elements composing a photometer, as will be more particularly described hereinafter.

In the drawings, Figure 1 shows in plan view the photometer and photometer-stand with the lamps upon the latter. Fig. 2 shows in elevation the said photometer-stand. Fig. 3 shows in detail one of the contact-pieces upon the standard. Fig. 4 shows the spring-clip by which the revolving portion of the stand may be locked in certain positions.

In the manufacture of incandescent electric lamps it is necessary to calibrate each lamp to determine either its candle-power with a standard current or the amount of current necessary to give it a standard candle-power. To facilitate this operation I have designed the following apparatus, in which X, Fig. 2, is the table to which the standard S is screwed. Within the standard is a vertically-adjustable spindle, A, held in position by the thumb-screw N. Upon the upper end of the spindle A is a revolving bearing, upon which two or more arms, P P', of insulating material, are fastened in any suitable manner. At the outer end of each arm is a lamp-socket, M M'. Within these sockets are removably placed the lamps l l'. Cables formed of two electric wires insulated one from the other, and designated by the letters E E' in Fig. 2, connect the electrodes of each lamp-socket with the binding-screws D F and D' F' on each of the revolving arms, respectively.

The binding-screw D is connected with the contact-piece Y and the binding-screw F with the contact piece or brush H. In the same way D' and F' are connected, respectively,

with Y' and H'. The stationary contact-piece C is held to the top of the spindle A by the set-screw B and electrically connected with the said spindle. At a point below the revolving arms the rubber ring, shown clearly in Fig. 3, is fastened to the standard A, and the contact-piece I is thus fastened to the said spindle, but insulated therefrom. Upon the contact-piece I is the binding-screw K. These contact-pieces may be rigid or they may be of a yielding nature, such as well-known forms of contact-brushes, contact-springs, &c.

The bearing Q, (shown in detail in Fig. 4,) to which the arms P and P' are fastened, has a spring-clip, T. (Clearly shown in Fig. 4.) This spring-clip drops into one or other of the notches V upon the spindle A, as shown in Fig. 2, whenever a lamp, as l, is in position to be calibrated, as indicated in Fig. 1.

The electrical connections are as follows: The current enters through the connection W, as shown in Fig. 2. It follows the directions indicated by the arrows through the standard S, spindle A, contact-piece C, contact-piece Y, the binding-screw D, through one wire of the cable E, through the lamp-circuit l, back through the other wire of the cable E, the binding-screw F, the contact-piece or brush H, contact-piece I, the binding-screw K, and the wire W', to the other terminal of the external circuit.

Fig. 1 shows the standard lamp L and the photometer-rack R with its scale and the sliding gage G, which has its two pieces of oil-paper and the disk of opaque material between them, in the manner customary in photometers of this type.

In operation one man can devote all his attention to the photometer and the variable resistance which determines the calibration of the lamp which is in line with the photometer while another operator is removing another lamp already calibrated and placing a third in the socket thus vacated. When this operation is completed, the spring-clip T is lifted and the stand revolved until it locks in position for a repetition of the operation.

While I have shown but two arms in the revolving portion of the stand, it is evident that three or more might be used without in

any way varying my invention or requiring such changes in construction as necessitate further illustration.

Having therefore described my invention, 5 both in essence and detail, what I claim as new, and desire to protect by Letters Patent, is—

1. A revolving photometer-stand which has the following parts in combination: two revolving arms, each of which carries a socket 10 for an electric lamp, a set of two contact-pieces on each arm and connections between the contact-pieces and the electrodes of the lamp-socket, together with a standard which 15 has two stationary contact-pieces insulated one from the other and corresponding to the sets of contact-pieces on the revolving arms, which stationary contact-pieces form the terminals of an external electric circuit, substantially as described.

2. A revolving photometer-stand which has the following parts in combination: two revolving arms, each of which carries a socket 20 for an electric lamp, a set of two contact-pieces on each arm, and connections between these contact-pieces and the electrodes of the lamp-socket, together with a standard which 25 has two stationary contact-pieces insulated

one from the other and corresponding to the sets of the contact-pieces on the revolving arms, and a spring-clip for locking the revolving arms in one position when the stationary contact-pieces touch any one of the revolving sets of contact-pieces, substantially as described.

3. The combination, in a photometer, of the stationary standard lamp, the sliding gage, and the revolving photometer-stand, which has sockets for two lamps, whereby while one lamp is being calibrated a second lamp 40 may be removed and a third substituted in its place, substantially as described.

4. The combination, in a photometer, of the stationary standard lamp, the sliding gage, and the revolving photometer-stand, which 45 has sockets for two lamps and electric connections for the same, whereby while one lamp is being calibrated a second lamp may be removed and a third substituted in its place, substantially as described.

In testimony whereof I affix my signature in presence of two witnesses.

JAMES WARD PACKARD.
